(57) **CLAIM**

The ornamental design for an ultrasound probe as shown and described.

DESCRIPTION

FIG. 1 is a perspective view of a first embodiment of an ultrasound probe design;

FIG. 2 is a right view thereof;

FIG. 3 is a left view thereof;

FIG. 4 is a front view thereof;

FIG. 5 is a rear view thereof;

FIG. 6 is a top plan view thereof;

FIG. 7 is a bottom plan view thereof;

FIG. 8 is a perspective view showing the tip of the ultrasound probe design;

FIG. 9 is a perspective view of a second embodiment of an ultrasound probe design;

FIG. 10 is a right view thereof;

FIG. 11 is a left view thereof;

FIG. 12 is a front thereof;

FIG. 13 is a rear thereof;

FIG. 14 is a top plan view thereof;

FIG. 15 is a bottom top plan view thereof;

FIG. 16 is perspective view showing the tip of the ultrasound probe design;

FIG. 17 is perspective view of a third embodiment of the ultrasound probe design;

FIG. 18 is a right view thereof;

FIG. 19 is a left view thereof;

FIG. 20 is a front view thereof;

FIG. 21 is a rear view thereof;

FIG. 22 is a top plan view thereof;

(Continued)

FIG. 23 is a bottom plan view thereof; and, FIG. 24 is a perspective view showing the tip of the ultrasound probe design. The broken lines in the figures depict portions of the ultrasound probe that form no part of the claimed design.
